Atty.

UNITED STATES PATENT OFFICE.

JOHN S. GENDALL, OF WOODMONT, CONNECTICUT.

JIBING BUFFER.

Application filed May 18, 1922. Serial No. 561,830.

To all whom it may concern:

Be it known that I, JOHN S. GENDALL, a citizen of the United States, residing at Woodmont, in the county of New Haven and State of Connecticut, have invented a new and Useful Improvement in Jibing Buffers; and I do hereby declare the following, when taken in connection with the accompanying drawings and the characters of reference marked thereon, to be a full, clear, and exact description of the same, and which said drawings constitute part of this application, and represent, in—

Fig. 1 a plan view, partly in section, of a jibing-buffer constructed in accordance with my invention.

Fig. 2 a side view of the same.

Fig. 3 an end view thereof.

Fig. 4 a sectional view, on the line 4—4 of Fig. 1.

This invention relates to improvement in jibing-buffers adapted for use in sailing vessels. The sheets for the sails of sailing vessels pass through a block, which is connected with a stationary eye, or with a block which travels on the taffrail, and when a vessel is jibed over, an enormous strain is placed upon the spars. The object of this invention is to provide a yielding bearing for the sheet-blocks, so that when a vessel is jibed, or running in a high sea, the strain on the spars, blocks and sheets will be relieved, and the invention consists in the construction as hereinafter described and particularly recited in the claims.

In carrying out my invention, I employ two bases 5 and 6 adapted to be firmly secured to the deck, rail or other part of a sailing vessel, as required. These bases are formed with upwardly-projecting flanges 7 and 8, between which extend rods 9 and 10 firmly secured to the flanges 7 and 8 by nuts 11. Upon the rod 9 is a sleeve 12, and upon the rod 10 is a corresponding sleeve 13. The rods 9 and 10 extend through plates 14, 15, 16 and 17. The plates 15 and 16 rest against the ends of the sleeves 12 and 13, and between the plates 14 and 15 are springs 18 and 19, and between the plates 16 and 17 are springs 20 and 21. Extending through

the plates 16 and 17 is an eye-bolt 22 having a nut 23 applied to its outer end, and extending through the plates 14 and 15 is an eyebolt 24 having a nut 25 applied to its outer end, and on the bolt 22, between the plates 16 and 17, is a spring 26, and on the bolt 24, between the plates 14 and 15, is a spring 27. Passing through eyes 28 and 29 of the bolts 22 and 24 are links 30 and 31, preferably connected by a ring 32, with which a regular sheet-block may be connected.

A strain upon the bolt 22 will first tend to draw the plate 17 inward, against the pressure of the springs 20 and 21 and against the pressure of spring 26, and a continued draft upon this bolt will compress the springs 18, 19 and 27. On the other hand, a strain upon the bolt 24 will first draw the plate 14 against the pressure of the springs 18, 19 and 27, and eventually, through the sleeves 12 and 13, be resisted by the springs 20, 21 and 26, so that a strain in either direction is taken by six springs. When a vessel is jibed over for the purpose of saving time, or for any other various causes, this device takes the strain off of the spars, and there is no sudden jerk or strain, as the jibing-buffer yields with the strain.

The device is also useful when a vessel is close-hauled on the wind, going to windward in a head beat sea, with the main sheet flat aft, as the buffer will yield in the sea-way and not tie the vessel up, so that the vessel can carry her sheets flatter and will beat to windward and kill foot faster.

I claim:

1. A jibing-buffer comprising two bases connected together by two rods, four plates on said rods, sleeves on said rods between the intermediate plates, eyebolts extending through the plates at opposite ends of the sleeves and connected with the outer plates, springs on said rods and bolts between said plates, and means for connecting a sheet-block with said eyebolts.

2. A jibing-buffer comprising two rods, means for suitably supporting them in parallel position, four plates through which the said rods extend, sleeves on said rods be-

tween the intermediate plates, eyebolts having their eyes between said sleeves, and extending outward through said plates, means for coupling said eyebolts with the outer plates, springs on said rods and eyebolts, and means for connecting a sheet-block with said eyebolts.

In testimony whereof, I have signed this specification in the presence of two subscribing witnesses.

JOHN S. GENDALL.

Witnesses:

MARY A. McCORMACK,

CHARLES F. FARREN.
